US0D1106683S

(12) United States Design Patent (10) Patent No.: US D1,106,683 S
(45) Date of Patent: * Dec. 23, 2025

(54) BAG DIVIDER

(71) Applicant: Lane Life Designs, LLC, Madeira, OH (US)

(72) Inventors: Heather L. Riddleman, Madeira, OH (US); Meggin N. Musser, Madeira, OH (US)

(73) Assignee: Lane Life Designs, LLC, Madeira, OH (US)

() Term: 15 Years

(21) Appl. No.: 29/978,902

(22) Filed: Dec. 16, 2024

Related U.S. Application Data

(63) Continuation of application No. 29/952,972, filed on Jul. 18, 2024, now Pat. No. Des. 1,054,211, which is a continuation of application No. 29/872,379, filed on Mar. 12, 2023, now Pat. No. Des. 1,036,125.

(57) CLAIM

The ornamental design for a bag divider, as shown and described.

DESCRIPTION

FIG. 1 is a front perspective view of a bag divider, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The uniform broken lines in the figures illustrate portions of the bag divider that form no part of the claimed design. The dot-dash broken lines in the figures represent boundaries that form no part of the claimed design.

1 Claim, 5 Drawing Sheets
